Barton J. Snow,
By Granforth, Esq., Chaffey & Miles,
Attys.

UNITED STATES PATENT OFFICE.

BARTON S. SNOW, OF BATAVIA, ILLINOIS, ASSIGNOR TO T. W. SNOW CONSTRUCTION CO., OF CHICAGO, ILLINOIS, A CORPORATION OF ILLINOIS.

SAND-LIFTING APPARATUS.

Application filed April 17, 1922, Serial No. 554,330. Renewed February 1, 1924.

To all whom it may concern:

Be it known that I, BARTON S. SNOW, a citizen of the United States, residing at Batavia, in the county of Kane and State of Illinois, have invented a new and useful Improvement in Sand-Lifting Apparatus, of which the following is a specification.

My invention relates, more particularly, to apparatus by which sand, and other relatively finely divided material, may be elevated to a desired point of storage, or discharge; and more especially to apparatus provided for this purpose and involving the use of fluid pressure, as for example compressed air, for effecting the lifting of the material.

Apparatus of the general type above referred to as commonly provided involves the provision of a receptacle into which the sand to be elevated is discharged, this receptacle having an opening through which fluid pressure, as for example air, is introduced into the upper portion of the receptacle, with a pipe opening at its lower end into the receptacle adjacent the bottom of the latter and extending to the point of elevated discharge, the introduction of the fluid pressure into the tank serving to force the same upwardly through the pipe. The provision of apparatus as stated, instead of producing a uniform upward discharge of the same through the pipe, has the effect of causing the sand to become bunched, so to speak, in the pipe, which is objectionable, particularly where the pipe is formed with portions extending at angles to each other, which is often the case and which afford surfaces which extend more or less horizontally, as the same becomes lodged on these surfaces and obstructs the passage of the sand to the point of discharge.

My primary object is to provide a novel and simple method and apparatus which will not present the objection stated, whereby interruption of the sand-lifting operation will be avoided.

Referring to the accompanying drawing:

Figure 1 is a view in elevation, partly sectional, of sand-elevating apparatus constructed in accordance with my invention, and suitable for carrying out my improved method, a portion only of the piping through which the sand is conveyed to the point of discharge being shown; and Figure 2, an enlarged section taken at the line 2 on

Fig. 1 and viewed in the direction of the arrows.

In the particular construction shown the hopper into which the sand, or other material to be elevated, is dumped, is represented at 3, the outlet 4 of this hopper communicating with an opening 5 in the top wall 6 of the tank 7 into which the sand, prior to elevating it, discharges, the inlet 5 being provided with any suitable valve means such as those shown and which are in accordance with common practice and involve a ball 8 forming the valve proper which is carried on the lower end of a rod 9 and serves when raised to the position shown in Fig. 1 to close the inlet 5, the rod 9 being connected with any suitable means for releasably holding it in the position shown. The pipe for conveying fluid pressure, as for example compressed air, into the upper portion of the tank 7, is represented at 10, this pipe being in communication with any suitable source (not shown) of suitable fluid pressure.

The top wall of the tank 7 is shown as formed of two sections 11 and 12, the section 11 being formed at its marginal edge with an annular depending flange 13 telescoping with the cylindrical side wall of the tank 7 and connected therewith as by the rivets 14, the section 11 containing an opening 15 centrally disposed therein. The section 12 is of a diameter greater than the diameter of the opening 15 and overlaps the wall of the opening 15 throughout the extent of the latter, as shown, in which position it is secured, as by the bolts 16, an airtight joint being made between these sections. The inlet 5 and the opening through which the pipe 10 extends, as hereinbefore stated, are provided in the section 12, this section containing another opening 17 into which the upper, open, end of a pipe 18 extends and is secured, this pipe depending into the tank 7 and extending at its lower, open, end, adjacent the bottom wall 7^a of the tank 7. The piping through which the sand is delivered to the elevated point of discharge, is represented generally at 19, the lower end of this piping extending into, and being secured in, the upper end of the opening 17 in vertically spaced relation to the upper end of the pipe 18. The pipe 19 may have one or more portions angularly disposed relative to another or others thereof,

as for example as represented at 20, and so disposed that a horizontal surface, or surfaces, is presented within the course through which the sand travels, it being common in 5 apparatus of the character above stated, for a number of these substantially horizontal surfaces to be presented.

The inner wall of the opening 17, between the pipes 18 and 19, is annularly cored to 10 present an annular recess 21 having a restricted annular opening 22 communicating with the opening 17, the recess 21 being in communication with one end of a pipe 23, the opposite end of which opens into the 15 main feed pipe 10, at 24, the pipe 23 being preferably provided with a hand-operated valve 25 for regulating the flow of fluid pressure from the pipe 10 into the pipe 23 and thence into the recess 21.

20 In the operation of the apparatus the sand to be elevated is permitted, by opening the valve 8, to charge into the tank 7, and the supplying of compressed air to the pipe 10 serves to cause compressed air to 25 flow into the tank 7 above the sand therein and also into the recess 21, the air entering the top of the tank serving to force sand upwardly through the pipe 18 and the air which discharges from the recess 21 into the 30 stream of sand and air rising through the opening 17 serves to agitate the same, diluting it with air and producing a condi-

tion whereby the objectionable bunching of the sand hereinbefore referred to and the lodging of the sand upon any substantially 35 horizontal portions provided in the piping 19, is avoided.

While I have illustrated and described a particular construction of apparatus embodying my invention and have shown a 40 particular apparatus for practicing my improved method, I do not wish to be understood as intending to limit my invention thereto as the novel features of the apparatus may be embodied in other forms of 45 apparatus and the method practiced by the use of the apparatus.

What I claim as new, and desire to secure by Letters Patent, is:

In material-lifting apparatus, the combination of a tank for the material to be lifted, a conduit opening into said tank and through which the material is elevated, means for subjecting the material in the tank to fluid pressure for forcing it 50 through said conduit, and a second conduit for fluid pressure, said second conduit opening through the wall of said first-named conduit above the end thereof opening into said tank, in a plane substantially at right 55 angles to said first-named conduit and throughout the circumference of the latter.

BARTON S. SNOW.
